ORNAMENTAL WOVEN FABRIC AND METHOD OF MAKING THE SAME

William Teres, New York, N. Y.

Application August 15, 1936, Serial No. 96,286

2 Claims. (Cl. 26—69)

My present invention relates generally to textiles, and has particular reference to a new ornamental woven fabric and a method of making the same.

The present novel fabric is of the moiréed type, and the novel ornamentation is characterized by a series of spaced wavy moiré stripes, and a series of spaced ornamental spot areas which co-operate in a unique manner with the moiré stripes.

An ornamental textile of the present improved character employs as its basis a woven ground fabric of the ribbed type, i. e., a fabric in which the number of warp threads per inch bears a relatively high ratio to the number of filler threads per inch. This type of weave, especially where the filler threads are of highly twisted yarn, produces a ribbed effect, in itself well known, by virtue of the fact that the filler threads remain substantially straight and parallel while the warp threads necessarily undulate up and down around the fillers.

It is well known that a ribbed fabric, especially where the warp threads are composed of artificial silk of the acetate type, lends itself readily to a moiréing procedure. Before describing the details of my present invention, I will point out that the moiréing treatment which I employ is the one whereby the fabric is doubled upon itself along a line substantially parallel to the weft, and is then subjected to heat and pressure between rollers or the like. When the fabric is doubled upon itself, the two superposed plies are purposefully arranged slightly askew with respect to each other, so that the ribs of the upper ply are not truly parallel to the ribs of the lower ply. When these superposed plies are subjected to heat and pressure, the relative angularity of the ribs results in producing a series of spaced wavy moiré stripes.

My present invention is predicated upon the discovery that an unusual novel effect of ornamentation can be achieved by initially incorporating in the ribbed fabric, during its weaving, a series of dobby figures or spots of particular character. More particularly, the dobby figures are arranged in a regular pattern, preferably with the figures in alignment both lengthwise and transversely of the fabric. Each figure is woven in such a manner that it defines a slightly raised area of sufficient density and compactness, so that it will have an embossing effect when the fabric is subsequently doubled upon itself for the moiré treatment.

The unusual ornamental effect is produced by

virtue of the fact that, during the heat and pressure of the moiré procedure, the dobby figures produce similar impressions on the opposite ply of the fabric; and, at the same time, they affect the continuity of the wavy moiré stripes. The result is that in the finished fabric there are two sets of ornamental spot areas, one set being composed of the original dobby figures, and the other set being arranged in relatively oblique relationship to the first set and consisting of the spot impressions of the dobby figures. These two sets of spot areas are interspersed in a pleasing arrangement among a series of spaced wavy moiré stripes, and the unique character of the present novel ornamentation is enhanced by the fact that each moiré stripe has its wavy continuity interrupted and laterally displaced whenever it encounters one of the spot areas.

I achieve the foregoing objects, and such other objects as may hereinafter appear or be pointed out, in the manner illustratively exemplified in the accompanying drawings, wherein—

Figure 1 is a plan view of a portion of ground fabric having spaced dobby figures woven thereinto;

Figure 2 is an enlarged plan view, somewhat diagrammatic in character, of a portion of the finished textile, Figure 2 representing in a general way the area delimited by dot-and-dash lines in Figure 1;

Figure 3 is a greatly enlarged cross-sectional view taken substantially along the line 3—3 of Figure 2; and

Figure 4 is a photographic plan view of a portion of ornamental textile constructed in accordance with the present invention and clearly showing its unique features.

In the portion of fabric indicated in Figure 1, it may be pointed out that the warp threads, which are preferably of the acetate type, extend vertically as viewed in this figure. At 10 I have indicated one lateral margin of the fabric, and at 11 I have indicated the opposite lateral margin, these margins being sevaged in accordance with usual weaving practice. While not shown in Figure 1, it will be understood that the fabric is of the ribbed type, i. e., a series of parallel ridges or ribs extending transversely across the fabric from the margin 10 to the margin 11. This ribbed effect is produced, as hereinbefore pointed out, by employing a high ratio between the number of warps per inch and the number of fillers per inch, and also by preferably using a highly twisted filling.

In accordance with my invention, the ground

fabric, when originally woven, is caused to embody a series of dobby figures which are represented in Figure 1 by small black spots. Preferably, these figures are arranged in transverse 5 rows, as shown in Figure 1, and, preferably, the distance between the figures of each row is approximately the same as the distance between the rows themselves.

While my invention is not limited to any particular type of dobby figure, it is essential that each figure be so woven that it defines a relatively dense and compact area. One way of accomplishing this result is illustrated most clearly in Figure 3.

15 In Figure 3, the reference numeral 12 is applied to the filling threads, and the reference numeral 13 is applied to the warp threads. It will be observed that I have shown the ground fabric of the plain woven type, wherein the warp threads 20 interweave upwardly and downwardly with the filling threads. Wherever a dobby figure of the present character is desired, the warp thread is permitted to float over three fillers and then under three fillers, the adjacent warp being similarly but oppositely arranged. This method of 25 weaving produces a substantially rectangular dobby figure of sufficient density and compactness to carry out the purposes of my invention. I have illustratively shown the warp threads passing over three fillers and then under three fillers, and a total of sixteen warps may thus be woven 30 to form the present dobby figure; but it will be understood that this particular rectangular dobby figure is referred to and herein illustrated merely by way of example and that my invention 35 is not restricted to these details of dobby weaving.

The next procedure, in carrying out my invention, is to double the fabric of Figure 1 upon itself along a line substantially parallel to the weft. I have not deemed it necessary to illustrate this, because this mode of producing a moiré effect is known per se. Suffice it to point out that the two plies are purposely arranged in 40 a slightly askew relation, one to the other, and that the superposed plies are then passed between rollers or the like and subjected to heat and pressure. The final result is illustrated most clearly in Figure 2. The reference numeral 14 is applied to the original dobby figures. The reference numeral 15 is applied to a series of spaced 45 spot impressions which are the result of pressing the dobby figures of one ply into the opposite ply during the heat and pressure treatment. It will be observed that the impressions 15, while aligned and spaced substantially like the figures 14, are, nevertheless, arranged along oblique lines. This arises from the askew relationship between the 50 superposed plies during the moiré treatment.

60 It will further be observed that the fabric now embodies a series of spaced wavy moiré stripes which I have designated by the reference numeral 16. The exact disposition and spacing of these stripes cannot be foretold during the production 65 of the present fabric. Sometimes the stripes are quite "wild", but in general they are arranged in spaced relationship and extend in a substantially longitudinal direction, i. e., substantially in the direction of the warp threads of the fabric.

Upon observing Figure 2, it will be noted that the smooth continuity of the waviness of the moiré stripes is interrupted where they encounter the spot areas 14 and 15. The interruption usually manifests itself by a lateral displacement of the stripe, but sometimes the interruption is of a different character and one stripe may seem to merge with the adjacent one, or to vary from its basic waviness in some other manner. This result is directly attributable not only to the fundamental nature of the moiré treatment, but also to the spacing and general nature of the original dobby figures.

The ultimate unique ornamental effect is characterized by the spaced dobby figures, by the spaced wavy moiré stripes, by the spaced spot impressions made by the dobby figures, themselves, during the moiré treatment, and by the fact that the moiré stripes are interrupted in continuity at the dobby figures and also at the spot impressions thereof.

It will be understood that my invention is applicable to fabrics in a variety of ways. For example, the present unique ornamentation may extend completely across the full width of the 25 fabric, or it may extend across only a partial width. Sometimes it may be desirable to provide the present ornamentation in spaced areas, and to provide other ornamentation or an absence of ornamentation in the intermediate 30 areas.

In general, it will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. An ornamental moiréed textile, comprising a ribbed woven fabric having spaced dobby figures, each figure being so woven that it defines a raised area sufficiently dense and compact to have an embossing effect when the fabric is doubled upon itself, the ornamentation consisting of said dobby figures, of spaced wavy moiré 45 stripes, and of spot impressions made by the dobby figures themselves during the moiré treatment, the wavy moiré stripes being interrupted in continuity at the dobby figures and also at the spot impressions thereof.

2. The method of making an ornamental moiréed textile, which consists in first weaving a ribbed fabric having spaced dobby figures, each figure being so woven that it defines a raised area sufficiently dense and compact to have an 60 embossing effect when the fabric is doubled upon itself, and finally doubling the fabric upon itself and subjecting it to heat and pressure so as to produce a series of spaced wavy moiré stripes and a series of spot impressions made by said dobby 65 figures.

WILLIAM TERES.
